CENTRIFUGE FILTRATION

Robert L. Dega, Utica, Mich., assignor to General Motors Corporation, Detroit, Mich., a corporation of Delaware
Filed May 11, 1959, Ser. No. 812,354
1 Claim. (Cl. 233—2)

This invention relates to centrifuges for the treatment of fluids and more particularly to centrifuges in which a filtration aspect is employed to enhance the effectiveness of fluid purification.

In the clarification of fluids containing high proportions of solids, it is often desirable to combine a filtration feature even though the solids tend to load or clog a centrifuge employed in the process, this clogging necessitating frequent dismantling and cleaning of the apparatus.

An object of the present invention is to provide an improved centrifuge in which a fluid being clarified may be subjected to a filtering action. Another object of the invention is to provide a centrifuge in which a filtering element is incorporated to aid in the clarification and in which the filtering element is continuously relieved of contamination simultaneous with the centrifugal action.

A feature of the invention is a hollow rotor having partitions dividing the interior into three chambers, vanes being located in at least one of the chambers to promote centrifugal action and consequent fluid flow into the other two chambers and baffle means in one of the latter to aid in guiding a portion of the flow along one side of a filtering element.

These and other important features of the invention will now be described in detail in the specification and then pointed out more particularly in the appended claim.

In the drawings:

FIGURE 1 is a sectional view taken along the line 1—1 in FIGURE 3 and showing a centrifuge in which the present invention is embodied, a portion of the casing for the power source being shown;

FIGURE 2 is an enlarged sectional view of a portion of the rotor shown in FIGURE 1; and

FIGURE 3 is a sectional view looking in the direction of the arrows 3—3 in FIGURE 1 and taken at various levels better to describe the construction.

The centrifuge disclosed is shown to comprise a support casing as generally indicated at 10. This support constitutes a shell with a top platform 12 to which a cylindrical casing 14 is attached with its axis vertical. Within the casing 14 is mounted a casting 20 defining two flow passages 22 and 24. A pipe connection 26 extends outwardly through the casing 14 and is joined to the casting 20 to cooperate with passage 22 in forming a flow inlet passage. A pipe connection 28 is similarly associated with the passage 24 to form an outlet passage. This connection also extends outwardly through the wall of the casing 14.

The support 10 encloses an electric motor, not shown in the drawings, but which motor is arranged to drive a vertical shaft 30. A suitable coupling 32 is joined to the upper end of the shaft 30 and the upper end of the coupling is fixed to the end of a hollow shaft 34 which is journaled in a partition 36 separating the two passages 22 and 24. Openings 38 through opposite walls of the shaft 34 give communication between the interior of that shaft and the passage 22. The upper portion of the casting 20 is bored to receive a ball bearing arrangement 40 and a suitable sealing unit 42. The ball bearing and sealing arrangement cooperate in forming a leakproof journal of a downwardly extending sleeve or hollow shaft 44. The shaft 44 is open at its bottom end and surrounds the shaft 34 to define a discharge passage communicating with the outlet passage 24. The upper end of the

2

sleeve 44 bears a flange 46 which bears down upon the inner race of the ball bearing 40 and which is fixed to the main casing 48 of a rotor by means of screws such as screw 50. A gasket 52 is interposed between the casing 48 and the sleeve flange to insure that no leakage occurs from the rotor. The casing 48 is centrally apertured as at 54 to form a continuing or registering passage with the discharge passage afforded by the shaft 44 around the shaft 34. The casing 48 of the rotor is located above an opening 54 formed in the casing 14 and the periphery of the casing 48 extends outwardly and is of greater diameter than the diameter of the opening 54. The top 10 of the casing 48 is closed by means of a cover member 56 which bears a sealing gasket 58 and is held in position by means of a split ring 60 and screws such as screw 62. The split ring is so made as to tend to expand to a diameter greater than that of the cover member 56 and enter a groove 64 formed in the inner wall surface of the casing 48. A shoulder 66 is formed in the casing 48 determining the exact location of the cover member within the casing. An opening 68 is formed in the cover member 56 in alignment with the shafts 34 and 44. Coaxial with this opening is a calibrating ring 70 which is interposed between the cover member 56 and an outlet ring 72 which is fixed to the cover member by screws such as the screw 74.

An annular trough 76 is mounted around the casing 14 and the annular outer wall of the trough is joined by means of an annular wall member 78 to a stiffening ring 30 80 which surrounds the upper end of the casing 48 but is spaced therefrom. A circular cover 81 is formed with a rolled edge 82 for detachable joinder to the upper marginal portion of the annular wall member 78.

The rotor cover member 56 is integrally provided with 35 eight spaced and radially extending ribs 84. Each of these has one end terminating at the edge of the opening 68 and its other end conforming with or abutting the inner wall of the casing 48.

Partitions are formed in the rotor within the casing 48. These partitions comprise a cuplike element 86 comprising two cylindrical walls 88 and 90 which are joined by an annular ring 92 and a bottom wall 93. The cuplike element cooperates with an inner cover 96 in defining a centrifugal chamber 98. The bottom wall 93 is apertured for connection of the chamber 98 with the upper end of the shaft 34. The cuplike element 86 is spaced from the rotor casing 48 to define a liquid chamber 96' as well as an annular passage 97 the inlet to which is divided in effect by sixteen arcuate dirt passages and eight relatively restricted ports C as will further appear. The inner cover 96 contacts the ribs 84 to coact with the cover member 56 in defining eight radial dirt chambers 99 which connect the annular passage 97 to the outlet 50 55 68. These chambers 99 are shallow when considered in the direction of the rotor axis as may be seen in FIGURE 1.

Eight radial vanes 100 are located in vertical planes within the centrifugal chamber 98, the inner edges of 60 these vanes terminating at the junctions with the shaft 34 and their outer edges being welded to the walls 88 and 90.

A cylindrical lining 102 is arranged within the liquid chamber 96 beneath the level of the cylindrical wall 88. Eight vanes 104 extend from the lining 102 and close to 65 annular filter means 106 and four small vanes 110 traverse the annular passage 97. Additional vanes 112, four in number, radially divide the liquid chamber 96' and extend from the annular filter means 106 to the lower end of the shaft 44. The vanes 110 lie in the same planes as do four of the vanes 100 and four of the ribs 84.

The vanes 112 lie in the same planes as the other four vanes 100.

The filter means 106 comprises laminated paper impregnated with a thermoset resin, this paper being sandwiched between two cylinders of perforated thin metal. Baffle means comprising eight imperforate plate members 120 are arranged in series around the periphery of the liquid chamber 96. Each plate member has its vertical and opposed edges in contact with the lining 102 and the adjacent plate members. An intermediate portion of each plate member is constrained between the inner edge of a vane 104 and the filter means 106. The lower edge of each plate member 120 terminates at a level 121 short of the bottom wall of the rotor.

Eight arcuate openings 122 are formed in the partition or ring 92 to connect the centrifuge chamber 98 with the liquid chamber 96 outside the baffle means or plates 120. Each opening 122 straddles a vane 100 and a vane 104. The baffle means therefor separate the peripheral zone of the liquid chamber into up-flow passages B alternating with pairs of down-flow passages A. The up-flow passages B each communicates by means of a small triangular orifice C with the annular passage 97 leading to the dirt chambers 98. Each orifice C is partially defined by the lower peripheral edge of the cylindrical wall 88. The inner portions of the rotor are firmly held in their positions by means of eight bolts 124 which extend through the inner cover 96 and the bottom wall 93 and are threaded into the main casing 48.

In operation of the device and assuming that the rotor is being rotated by means of the shaft 30, contaminated liquid is pumped by way of the inner chamber 22 through the ports 38 into the hollow shaft 34. This fluid flows upwardly into the centrifugal chamber 98 where the eight radial vanes 100 impart rotation and enhance outward flow of the fluid. Solid matter will be separated from the fluid against the inner surfaces of the cylindrical walls 90 and 88 as the liquid progresses to the extreme allowable diameters determined by the partitions. The liquid, thus partially clarified, then is directed downwardly through the arcuate openings 122 into the passages A outside the baffle plates 120. In those passages, it is subjected to the maximum centrifugal force while being positively driven. Further separation of the fluid constituents takes place in these passages with the primary or lighter liquid flowing downwardly and the secondary liquid or contaminant is forced outwardly against the inner wall of the lining 102 and then upwardly through the elongated arcuate ports D. The lighter liquid does not normally flow upwardly through the port D because of a dirt build-up explained below. It flows downward through the high centrifugal field and beneath the edges 121 of the baffle plates 120 into the upwardly directed passages B. In these passages, the lighter liquid flows through the filter means 106 which provides the proper degree of filtration desired and within reasonable flow rates. The pressure forcing the lighter liquid through the filter means is created by the differential radius of inlet and discharge inherent in the centrifuge construction. The filtering action under the high centrifugal field provides an effective and continual cleaning of the filter surface preventing undue accumulation of impurities thereon. This is accomplished because extremely fine particles will agglomerate and are more easily passed upwardly to join

the discharge from the arcuate ports D as the centrifugal force acts on the continually incoming flow. This agglomerate is forced against the walls of the baffle means but progresses upwardly to the triangular and restricted discharge ports C where there is a maximum build-up of centrifugal force. Once a dirt build-up in the annular passage 97 and the radial passages 99 is established, small additions of dirt within the rotor periphery will cause an equal amount of dirt or liquid to be discharged over the lip of the calibrating ring 70. Dirt discharged over the top of the ring 72 is ultimately collected in the trough 76 and may be periodically or continuously removed as will be understood.

Fluid clarified by centrifugal action and also by the filtering action passes from the filtering means 106 and while guided by the four vanes 112 in the liquid passage 96 is forced downwardly through the shaft 44 to the outlet passage 24 for discharge.

I claim:

20 A centrifuge including a hollow rotor mounted for rotation on a vertical axis, hollow shafts coaxial with said rotor and extending downwardly from the latter for admitting and discharging fluid, the upper end of said rotor having an upwardly directed central outlet for discharging solids, partitions in said rotor dividing the interior thereof into a vaned centrifugal chamber and two other chambers all coaxial with said rotor, said centrifugal chamber being interposed between said two other chambers and connected to one of said shafts for receiving untreated fluid from the latter, one of the said two other chambers being connected to said rotor outlet for receiving and conducting solids to the latter and being shallow in the direction of the rotor axis, the other of said two chambers being a liquid chamber surrounding 30 said one of said shafts, main large discharge openings arranged in a circular series in said partitions adjacent the periphery of said rotor and connecting said centrifugal chamber with the said liquid chamber, a series of other smaller discharge openings in said rotor located radially outside said main openings and adjacent the rotor periphery and arranged to connect said other two chambers, annular filter means located radially inwardly of said series of main openings and dividing the interior of said liquid chamber, baffle means surrounding said annular 35 filter means and arranged to direct the flow of solids from said series of main discharge openings from said liquid chamber and upwardly to said shallow chamber by way of said series of other smaller discharge openings and also to direct the flow of liquid downwardly and then 40 into contact with the exterior of said filter means, and said liquid chamber being connected to the other of said shafts for discharging clarified fluid from within said filter means downwardly from said rotor.
